(57) **CLAIM**

I claim the ornamental design for a structural beam for machines and devices, as shown and described.

DESCRIPTION

FIG. 1 is a front view of a structural beam for machines and devices as showing our new design.

FIG. 2 is a rear elevational view thereof.

FIG. 3 is a right side elevational view thereof.

FIG. 4 is a left side elevational view thereof.

FIG. 5 is a top plan view thereof.

FIG. 6 is a bottom view thereof.

FIG. 7 is a cross sectional view taken along line 7-7 in FIG. 1.

FIG. 8 is a cross sectional view taken along line 8-8 in FIG. 5; and,

FIG. 9 is a perspective view thereof.
